UNITED STATES PATENT OFFICE

151,205

DESIGN FOR A REAR VISION MIRROR OR SIMILAR ARTICLE

James W. Anderson, Jr., Detroit, Mich.

Application August 15, 1947, Serial No. 140,891

Term of patent 7 years

(Cl. D14—6)

To all whom it may concern:

Be it known that I, James W. Anderson, Jr., a citizen of the United States, residing in Detroit, county of Wayne, State of Michigan, have invented a new, original, and ornamental Design for a Rear Vision Mirror or Similar Article, of which the following is a specification, reference being had thereto to the accompanying drawings, forming a part thereof, in which

Fig. 1 is a top plan view of a rear vision mirror or similar article embodying a design in accordance with the present invention, the mirror being illustrated in the position it occupies when attached to the left-hand side of an automobile body.

Fig. 2 is a front elevation of the article shown in Fig. 1.

Fig. 3 is a side elevation taken from the left-hand side of the article shown in Fig. 1.

Fig. 4 is a side elevation taken from the right-hand side of the article shown in Fig. 1.

The characteristic features of my design reside substantially in the portions shown by means of full lines in the drawing.

I claim:

The ornamental design for a rear vision mirror or similar article, substantially as shown and described.

JAMES W. ANDERSON, JR.
